Attorney

UNITED STATES PATENT OFFICE.

EDGAR CLINTON JOHNSTON, OF EL DORADO, ARKANSAS, ASSIGNOR TO JOHNSTON FORMATION TESTING CORPORATION, OF EL DORADO, ARKANSAS, A CORPORATION OF DELAWARE.

WELL-FORMATION-TESTING DEVICE.

Application filed March 23, 1927. Serial No. 177,719.

The present invention relates to improvements in testing devices for use in connection with formation and drilling oil wells and the like and has for its principal object 5 to provide a simple and efficient means for accurately testing sands which are encountered during the drilling of the well.

One of the salient objects of the present invention is to provide a testing device of 10 the above mentioned character which includes an automatically operated valve structure, which will at all times be positive and efficient in its operation.

In drilling a well where a likely formation is struck, the operator of the drilling mechanism or apparatus will reduce the size of the hole that is being drilled by the method commonly known or called "rat holding". This rat hole is formed by employing 20 a bit of a smaller size than the one used to finish the hole.

One of the important objects of the present invention resides in the provision of a testing device, which may be readily and 25 easily secured on the lower end of the drill pipe, the testing device including a perforated plug which is adapted to enter the rat hole, in order to permit any fluid or gas to enter the tester. A tapered packer is associated with the tester at a point above the 30 perforated plug and this packer is adapted for cooperation with the upper portion of the rat hole for the purpose of preventing water and mud laden fluid from entering 35 the rat hole and subsequently the perforated plug. Means are further associated with the tester for permitting the fluid to pass upwardly therethrough and enter the drilling pipe. A normally closed valve is arranged 40 within the testing device, the same being opened by the weight of the tester and the pipe to which the device is attached, when the packer strikes the rat hole.

A further object of the invention is to 45 provide an emergency relief arrangement by means of which, should the testing device become stuck in any part of the well bore, as by the crumbling in of the walls of the well, fluid pressure may be supplied below 50 the tester, tending to facilitate the withdrawal upward of the drill tube and tester,

without necessitating troublesome, expensive and often futile fishing operations.

A further object is to provide a device of the above mentioned character which is simple in construction, inexpensive, strong and durable and further well adapted to the purposes for which it is designed. 55

Other objects and advantages will become apparent during the course of the following 60 description.

In the accompanying drawing, forming a part of this specification, and in which like numerals indicate like parts throughout the same: 65

The figure represents a vertical sectional view through the testing device embodying my invention, and showing the same in actual use, the valve being open.

In the drawing wherein for the purpose of 70 illustration is shown the preferred embodiment of my invention, the numeral 1 designates generally the tester. The same comprises the cylindrical casing 2 which is internally threaded at its upper and lower 75 ends. A bushing or fitting 3 is threaded at its lower end in the upper internally threaded end of the cylindrical casing 2 and the upper portion of the bushing has the bore 4 thereof enlarged to provide the socket 5. 80 This socket is internally threaded at its upper end whereby the bushing or head may be threaded on the lower threaded end of the drill pipe 6. The valve seat 7 is formed at the juncture of the bushing 3 with the socket 85 5, and the purpose of this valve seat will be hereinafter more fully described.

A bushing or head 8 is threaded at its upper end in the lower internally threaded end of the cylindrical casing 2, thereby providing 90 a unitary structure between the casing and the heads.

My improved tester further includes the provision of the stem 9, which is of a diameter slightly less than the diameter of the 95 bore 4 of the bushing 3, and through which the stem extends. This stem is formed with a longitudinal bore 10. A valve 11 is formed at the upper end of the stem and is arranged within the socket 5 for cooperation with the 100 valve seat 7. This valve is normally maintained in a closed position against the valve

seat by a suitable spring in the manner to be presently apparent. A tubular extension 12 is formed on the upper end of this stem 9 and this extension extends upwardly into 5 the lower end of the pipe 6 as is shown in the drawing. The upper end of the extension is formed with a square shoulder 13 whereby the stem may be rotated for engagement with or disengagement from the pipe 14.

10 This pipe 14 extends through the bore of the lower bushing 8 and the upper portion of the pipe extends into the cylindrical casing 2 and is internally threaded at its upper end for detachable engagement with the 15 lower threaded end of the stem 9. The connection 15 between the lower end of the stem 9 and the upper end of the pipe 14 will form a unitary structure.

The upper portion of this pipe is formed 20 with a series of fluid outlet openings 16, and the lower end of this vertical pipe 14 is externally threaded as is clearly shown at 17 in the drawing.

A suitable packing gland 18 is threaded 25 upwardly into the bore of the lower bushing 8 and the same surrounds the intermediate portion of the pipe 14. The bottom of the bushing 8 is formed with an enlarged cut out portion 19 to receive the tool engaging end of the gland 18.

A tapered rubber packer 20 is formed with a central bore and is adapted for disposition upon the lower threaded end of the pipe 14. A relatively thick plate formed with a 35 central threaded opening is threaded on the threaded end portion 17 of the pipe 14 and engages the top of the tapered rubber packer 20 in the manner clearly shown in the drawing and this plate is designated by the number 21. A heavy expandable coil spring 22 encircles the threaded portion 17 of the pipe 14 and is disposed between the bushing 8 and the plate 21. The upper end of the spring encircles the tool engaging end of the 45 packing gland 18 and is disposed within the cut out portion 19 formed in the bottom of the bushing 8. The lower end of this spring is disposed within an annular groove 23 formed in the top of the thick plate 21. The 50 expandable spring 22 normally urges the casing 2 and the bushings carried thereby upwardly so that the seat 7 will be held against the valve 11, thus cutting off communication between the socket 5 and the cylindrical casing 2 as is readily obvious from the construction shown in the drawing.

A tapered collar 24 is formed with a central threaded bore for threaded engagement on the threaded end of the pipe 14 and the 60 lower end of the tapered rubber packer 20 engages the upper face of this downwardly tapered collar and the collar provides means for preventing any possibility of the rubber packer 20 working downwardly on the lower 65 end of the pipe 14.

Adapted for cooperation with the lower end of the pipe 14 is the perforated hollow plug 25, the lower end thereof being closed. However, the closed lower end of the hollow plug is also formed with a series of perforations or openings similar to the openings formed in the side of the plug, and these openings are shown at 26. The perforated plug is threaded on the lower threaded end 70 of the pipe 14 and the upper open end of the plug will engage the lower end of the downwardly tapered collar 24 in the manner as clearly shown in the drawing. A reduced externally threaded neck portion 27 is formed on the lower end of the stem 9, the 75 same surrounding the bore 10. A cage 28 open at its upper end is threaded on this depending neck 27 and is arranged within the upper portion of the pipe 14. Confined 80 within the cage 28 and adapted for cooperation with the lower end of the bore 10 formed in the stem 9 is the ball valve 29. An expansible spring 30 normally urges the ball valve 29 against the lower end of the bore 10 for closing the same and the tension of 85 this coil spring is adjusted through the medium of a plate 31 slidable within the cage 28 and a bolt 32 is threaded through the bottom of the cage and engages the slidable plate 31 in the manner as clearly shown 90 in the drawing.

The ball valve 29 will normally prevent any possibility of any fluid passing upwardly through the stem 9. The operation of my improved testing device may be briefly 100 stated as follows:

After the rat hole A has been formed, the testing device is attached to the lower end of the drill pipe 6 and the same is lowered within the larger hole B, so that the lower 105 end of the pipe 14 will enter the rat hole and the hollow perforated plug 25 will be enclosed therein. The tapered rubber packer 20 will engage the upper edge of the rat hole and thereby form a closure for preventing any possibility of water or mud laden fluid from entering the rat hole from above. Due to the weight of the cylindrical casing and its bushings as well as the drill pipe 6 to which the casing is secured, the latter will 110 move downwardly on the pipe 14, against the tension of the coil spring 22, thus removing the valve seat from engagement with the valve and the fluid which enters the pipe 14 through the holes 26 in the perforated 115 plug 25 will pass upwardly through the pipe and be discharged into the casing through the outlet openings 16. The fluid will then pass upwardly through the bore 4 around the stem 9 and will further pass outwardly 120 through the drill pipe 6.

In using the present device, it may be found necessary to circulate the mud-laden fluid in the hole B and to this end, the fluid is admitted through the tubular extension 130

12 formed on the stem 9 and the pressure of this fluid will unseat the valve 29 and the fluid will then pass downwardly through the pipe 14 into the perforated plug 25 and will then circulate upwardly around the tester. Thus, should the tester stick in the well at any part of the bore above the rat hole, caused for instance by the crumbling in of the side walls of the well, fluid under pressure may be pumped into the well below the tester, and an upward pressure created which would greatly facilitate the lifting of the tester and the drill pipe attached thereto upwards to the surface, or as far up as may be desired.

When the device is in its lowermost position, the valve is open and manifestly when the device is lifted upwardly, the valve will be automatically moved to a closed position. 20 The provision of a valve structure of this character will obviate the necessity of having to provide any additional means for actuating the valve such as is employed with certain types of testing devices now in use. 25 With a testing device of the above mentioned character, the various formations encountered in drilling operations may be tested in a simple and efficient manner. The simplicity with which my device is constructed enables the parts to be readily and easily assembled and attached to the lower end of a drill pipe, and the device will at all times be positive and efficient in carrying out the purposes for which it is designed. 30 While I have shown the preferred embodiment of my invention, it is to be understood that various changes in the size, shape and arrangement of parts may be resorted to without departing from the spirit of the invention and the scope of the appended claims.

Having thus described the invention, what I claim as new and desire to secure by Letters Patent is:—

45 1. Apparatus for testing formations in oil wells, in which the well is provided with the usual bore and rat hole, comprising a drill tube projecting down into the well, a hollow cylindrical casing attached to the lower end of said drill tube, the upper head of said casing being provided with a valve seat and a bore beneath the same, and the lower head of said casing being provided with a stuffing box, a hollow valve stem carrying a valve, slidably mounted in said bore, a tube connected to the lower end of said valve stem and provided at its upper end with a series of perforations; said tube projecting down through said stuffing box, a perforated plug secured to the lower end of said tube and adapted to project down into the rat hole of the well, a packer mounted on said tube above said plug, a coil spring held under compression between said casing and said packer and normally adapted to hold said

adapted to hold said valve on its seat, and a spring impressed emergency valve located within said tube and normally closing the passage through said valve stem, but yielding to fluid pressure from above.

2. Apparatus for testing formations in oil wells, in which the well is provided with the usual bore and rat hole, comprising a drill tube projecting down into the well, a hollow cylindrical casing attached to the lower end of said drill tube, the upper head of said casing being provided with a valve seat and a bore beneath the same, and the lower head of said casing being provided with a stuffing box, a hollow valve stem carrying a valve, 70 slidably mounted in said bore, a tube connected to the lower end of said valve stem and provided at its upper end with a series of perforations and at its lower end with external threads, said tube projecting down 75 through said stuffing box, a perforated plug screwed on to the lower end of said tube and adapted to project down into the rat hole of the well, a tapered packer mounted on said tube above said plug, and adapted to 80 engage in the upper portion of said rat hole, a coil spring held under compression between said casing and said packer and normally adapted to hold said valve on its seat, and a spring impressed emergency valve located 85 within said tube and normally closing the passage through said valve stem, but yielding to fluid pressure from above.

3. Apparatus for testing formation in oil wells, in which the well is provided with the usual bore and rat hole, comprising a drill tube projecting down into the well, a hollow cylindrical casing attached to the lower end of said drill tube, the upper head of said casing being provided with a valve seat and a bore beneath the same, and the lower head of said casing being provided with a stuffing box, a hollow valve stem carrying a valve, 100 slidably mounted in said bore, a tube connected to the lower end of said valve stem and provided at its upper end with a series of perforations, said tube projecting down 105 through said stuffing box, a perforated plug secured to the lower end of said tube and adapted to project down into the rat hole of the well, a packer mounted on said tube above said plug, and a coil spring held under compression between said casing and said packer and normally adapted to hold said 110 valve on its seat.

4. Apparatus for testing formation in oil wells, in which the well is provided with the usual bore and rat hole, comprising a drill tube projecting down into the well, a hollow cylindrical casing attached to the lower end of said drill tube, the upper head of said casing being provided with a valve seat and a bore beneath the same, and the lower head of said casing being provided with a stuffing box, a hollow valve stem carrying a valve 115 120 125 130

slidably mounted in said bore, a tube connected to the lower end of said valve stem and provided at its upper end with a series of perforations and at its lower end with 5. external threads, said tube projecting down through said stuffing box, a perforated plug screwed to the lower end of said tube and adapted to project down into the rat hole of

the well, a tapered packer mounted on said tube above said plug, and a coil spring held 10 under compression between said casing and said packer and normally adapted to hold said valve on its seat.

In testimony whereof I affix my signature.

EDGAR CLINTON JOHNSTON.
